UNITED STATES PATENT OFFICE.

WILLIAM H. EVER, OF LAKWOOD, OHIO.

BUILDING CONSTRUCTION.

1,335,886.

Specification of Letters Patent.

Patented Apr. 6, 1920.

Application filed May 18, 1917. Serial No. 169,386.

To all whom it may concern:

Be it known that I, WILLIAM H. EVER, a citizen of the United States, and resident of Lakewood, county of Cuyahoga, State of Ohio, have invented certain new and useful Improvements in Building Constructions, of which the following is a specification.

This invention relates to building construction and more particularly to floors 10 and walls.

It is one of the objects of the invention to provide a reinforced concrete construction in which as many as possible of the various units may be made in a shop and 15 of such design and weight that they may be readily transported and erected.

Another object of the invention is to provide a concrete floor construction having girder reinforcements that may be shop-fabricated and so designed as to support the 20 floor beams and thus avoid the use of much false work.

Another object of the invention is to provide a standardized reinforced concrete beam adapted for use in floors of various 25 load capacities and also adapted for use as studding either in a bearing or non-bearing partition.

Other objects and the features of novelty 30 will be apparent from the following description taken in connection with the accompanying drawings, in which,

Figure 1 is a perspective view of a reinforced concrete beam embodying the invention;

Figs. 2 and 3 are perspective views of different forms of reinforcement for the beam shown in Fig. 1;

Fig. 4 is a perspective view of a hollow 40 tile or filler block to be used with the beams shown in Fig. 1;

Fig. 5 is a transverse section through a girder and floor slabs embodying the invention;

Fig. 6 is a perspective view of a floor slab embodying the invention;

Fig. 7 is a composite perspective of different types of partition construction embodying the invention; and

Fig. 8 is a perspective view of a block to be used in connection with the tile shown in Fig. 4.

Referring to the drawings, 10 indicates, generally, a concrete beam which is reinforced by two bars 11 and 12, preferably of the form described and claimed in my

prior application Serial No. 165,149 filed April 28, 1917. The bars 11 and 12 are arranged near the upper and lower sides of the beam and their ends may project from 60 the concrete, as shown in Fig. 1, for a purpose to be hereinafter described.

The bars 11 and 12 have legs or flanges along two sides thereof and are latticed together by bars 13, indicated in dotted lines 65 in Fig. 1. The reinforcement used in Fig. 1, is shown more clearly in Fig. 2, this form of reinforcement being particularly adapted for floor beams and it will be observed that the construction is such that the 70 beam will have substantially uniform strength irrespective of whether the beam is used in the position shown in Fig. 1 or relatively inverted. The lattice bars 13 may be riveted or bolted to the bars 11 and 12 and 75 the arrangement shown in Fig. 3 is preferably for reinforcing the studding of a partition, although either of the types of reinforcement shown may be used for beams or studding for cases where uniformity is desired throughout a building.

It will be observed that the beam 10 has shoulders or ledges 14 and 15, along opposite sides and substantially at the middle of the height of the beam, these giving to 85 the beam a T-shaped section and being of such width that one side of the beam is substantially double the width of the other side.

Referring to Fig. 6, it will be observed 90 that the floor slab is made up of a series of beams 10 spaced apart to receive between them hollow tile or filler blocks 16, shown in detail in Fig. 4. The blocks 16 may be of any suitable construction but should have 95 shoulders 18 and 19 along the middle of opposite sides, to engage with the ledges 14 and 15 of the beams and thus support the blocks with their upper and lower faces flush with the upper and lower sides of the 100 beams 10 so that the slab thus built up is ready to receive the wearing floor on the upper side and the ceiling plaster on the under side.

In Fig. 5, the manner of erecting a system of flooring is illustrated. A concrete girder 20, is reinforced by a built-up truss comprising the angle bars 21, 22, 23 and 24 connected together by lattice bars 25 and 26 and spacers 27 and 28 as described in my 105 prior application #165,149. After this built-up reinforcement is placed in position 110

on its supporting columns, the floor beams 10 are placed in position with ends on the upper bars 23, 24 of the girders. The girder reinforcements have the requisite strength 5 to support the beams so that false work for this purpose is avoided. Furthermore, the beams 10 may be factory-made, transported to the job, and erected. This expedites the construction greatly, since the beams can be 10 made in advance and transported to the job as fast as needed, thereby avoiding delay for the concrete to "set" and the accumulation on the job of large quantities of concrete materials, incident to the systems of reinforced concrete construction heretofore used.

Filler blocks 16 are placed between the beams 10 and closure slabs 29 are arranged at the ends of the filler blocks 16 to prevent 20 the cementitious materials, used in the girder 20, from flowing into the chambers in the blocks 16. The closure blocks 29 are shown in detail in Fig. 8. The ends of the bars 11 and 12, projecting from the ends of 25 the beams 10 are connected together, across the girders 20, by tie-rods 30, thereby increasing the strength and rigidity of the construction. Forms for the concrete, of the girders 20, are then placed in position 30 and the cementitious material laid, the same embedding the ends of beams 10 and filling the space to the level of the top of the beams. A floor thus constructed is as 35 strong as the equivalent reinforced concrete floor, as heretofore made, and has the advantage of being of less weight, requiring less materials, a minimum false work, and more rapid construction.

In Fig. 7, I have shown my invention as 40 applied to different types of partition construction. The studs 31, 32, 33 and 34 are

similar to the beams 10, but preferably reinforced, as illustrated in Fig. 3. The studs 31 and 32 are spaced to receive a single filler block 16, between them, the faces of the 45 block and studs alining so that the surfaces are ready to receive a plaster or stucco finish. For a lighter partition the studs may be arranged as 32 and 33 where the spacing is for two of the blocks 16, the studs 32 and 33 being relatively in reverse arrangement to permit the blocks 16 to interlock therewith and together as shown. For a heavy bearing partition the studs may be arranged side by side in interlocked arrangement, as are the studs 33 and 34. This arrangement may also be employed to provide a light column or a very heavy floor may be constructed by arranging the beams in a similar manner.

Having described the invention what is claimed is:

In reinforced concrete floor construction, the combination of a built-up truss forming the reinforcement of a girder, alined concrete beams extending in opposite directions laterally from said truss and having upper and lower reinforcing bars arranged with their ends projecting from the ends of the concrete, said bars being connected together 70 in said beams to form a truss and the ends of the beams being supported directly on the first-mentioned truss, tie rods oppositely connecting the said projecting ends of said upper and lower bars of alined beams together across the first-mentioned truss, and the first-mentioned truss, the ends of said beams and said tie rods being embedded in a monolith.

In testimony whereof I affix my signature. 80

WILLIAM H. EVERE
